UNITED STATES PATENT OFFICE

CHARLES HULTGREN, OF CHICAGO, ILLINOIS, ASSIGNOR TO S. KARPEN & BROS., OF CHICAGO, ILLINOIS, A CORPORATION OF WEST VIRGINIA

SOFA BED

Application filed June 11, 1926. Serial No. 115,199.

This invention relates particularly to sofa-beds of the type in which the front bed-section is adapted, in the folded condition of the structure, to occupy a superposed position over the rear bed-section.

The primary object is to provide an improved sofa-bed of this type.

The invention is illustrated in its preferred embodiment in the accompanying drawings, in which—

Fig. 1 represents a broken vertical sectional view of the improved sofa-bed in extended condition; Fig. 2, a broken vertical sectional view of the structure in sofa form, the section being taken just inside of one of the end standards of the main frame; Fig. 3, a broken vertical sectional view corresponding with the view shown in Fig. 1, but with some of the parts removed; Fig. 4, a broken plan sectional view taken as indicated at line 4—4 of Fig. 3; Fig. 5, a view corresponding with Fig. 3, but with parts omitted; Fig. 6, a view of one of the supporting plates carried by the end standards of the main frame; Fig. 7, a broken detail view showing a part of the fixture shown in Fig. 5; Fig. 8, a plan view of the mounting plate shown in Fig. 6; Fig. 9, a plan view of a portion of the fixture shown in Fig. 5; Fig. 10, a broken sectional view taken as indicated at line 10—10 of Fig. 3; Fig. 11, a detail sectional view taken as indicated at line 11 of Fig. 3; Fig. 12, a broken vertical sectional view taken as indicated at line 12 of Fig. 13; Fig. 13, a view corresponding with Fig. 3, but showing the structure in partially open condition; Fig. 14, a vertical sectional view corresponding with Fig. 3, but showing a slightly modified construction; Fig. 15, a broken plan sectional view taken as indicated at line 15—15 of Fig. 14; and Fig. 16, a view corresponding with Fig. 14, but with certain parts omitted.

Referring to the structure shown in Figs. 1—13, A designates a main frame comprising end standards A' (one shown) and a back A²; B, B, supporting plates secured to the inner surfaces of the lower portions of the end standards A'; B', mounting plates detachably connected with the supporting plates B, and further secured, at points 1, to

the end standards; C, a rear bed-section carried by links C' pivotally supported at points 2 on the mounting plates B'; and D, a front bed-section carried by parallel front links D', and parallel rear links D², these links having their front ends pivotally connected, respectively, at points 3 and 4, with the bed-section D and having their rear ends pivotally connected, respectively, at points 3^a and 4^a with the mounting plates B'.
55

The main frame A may be of any suitable construction. In the illustration given, the end standards A' may be assumed to constitute the arms of the sofa. These end standards are connected at their rear lower portions by members 5, and at their front lower portions by a member 6.
60

The supporting plates B are adapted to be secured, at points 7, with end standards A'. These plates are provided with inclined slots 8 which receive headed studs 9 with which the mounting plates B' are equipped. The supporting plates B are located near the front edges of the end standards, and the mounting plates B' project rearwardly 65 and are secured at the points 1 with the rear portions of the end standards, as by means of bolts equipped with wing nuts.
70

The rear bed-section C is shown as comprising a frame 10, upholstery springs 10^a mounted thereon, and a fabric 10^b enclosing said springs, the whole constituting a resilient bed-bottom.
75

The frame 10 of the rear bed-section preferably is carried by slides 11 connected by 80 pivots 12 with the upper ends of the links C'. Slides 11 are connected by a bar, or link, 13, which is secured to the pivots 12. The end-members of the frame 10 are slidably engaged by the slides 11. The bar 13 is connected by a link 14 with a lug 15 carried by the lever D², so that the links C' will be actuated through the medium of the rear levers D² of the front bed-section.
85

A radius bar 16 is connected at the point 2 90 with the mounting plate B' and at the point 16^a with the frame 10 of the rear bed-section. The front end of the link 16 swings through a short substantially vertical arc so that the rear bed-section is prevented from shift- 100

ing forwardly or rearwardly while it is being lifted or lowered. It will be understood that the structure of these fixtures is duplicated at each end of the sofa-bed.

5 The rear set of levers D^2 of the front bed-section is shown equipped with arms 17 with which are connected counterbalance springs 18 whose rear ends are connected with studs 19 carried by the mounting plates B' . It will 10 be noted that the counterbalance springs may assume either the position shown in Fig. 2 or the position shown in Fig. 3. In the one case, they will assist in opening the bed; and in the other case, they will assist in closing 15 the structure.

The front bed-section D comprises a frame 20 upon which is secured, or mounted, a spring bed-bottom, or mattress-section, D^3 . In the illustration given, the mattress-section 20 D^3 rises a considerable distance above the spring structure carried by the frame 10 of the rear bed-section C. A removable cushion C^3 is placed upon the spring structure of the rear bed-section, as shown in Fig. 1. 25 When the structure is to be converted to sofa-form, the cushion C^3 is removed; and after the structure has been folded, the cushion C^3 is placed upon the spring-bottom, or mattress-section, D^3 of the front bed-section, as 30 will be understood from Fig. 2.

The front ends of the rear levers D^2 of the front bed-section are preferably rigidly connected by means of a bar 4^b , the end-portions of this bar being rigidly secured to the front 35 ends of the levers D^2 and also journalled in the frame of the front bed-section D, as will be more readily understood from Fig. 12. Thus, the extremities of the bar 4^b afford the 40 pivotal connections indicated at 4. The purpose of the rigid connecting bar 4^b is to cause the levers of the front bed-section to turn in unison, and prevent racking of the structure.

The front edge-portion of the front bed-section D preferably is equipped with a pair 45 of folding legs 21 which are connected by pivots 21^a with the frame 20. The legs 21 are provided at their upper ends with short extensions, or lever-arms, which are connected by links 22 with the front ends of the front levers D' . The links 22 are connected with the levers D' by pivots 22^a which are disposed 50 near the pivots 3. The arrangement is such that the legs 21 will be thrown to vertical position when the structure is converted to bed-form, and will be thrown to folded condition in the operation of converting the structure to sofa-form.

The levers, or links, D' and D^2 are of angular form. When the structure is in bed- 60 form, the short arms of the levers stand in the position shown in Fig. 3, while the long arms of the levers extend substantially horizontally in a forward direction. The short arms of the front levers D' preferably are 65 equipped with studs, or stops, 23, upon which

the long arms of the rear levers D^2 can rest, as illustrated in Fig. 3. The mounting plates B' are also equipped with studs, or stops, 24, adapted to be engaged by the short arms of the rear levers D^2 when the structure is in the folded condition shown in Fig. 2.

In the modification shown in Figs. 14-16, the parts of the structure which correspond with the previously described construction 70 are designated by the same reference characters. The constructions correspond, except that the links C' have substituted therefor links C^2 , and the slides 11 and connecting link are dispensed with. In this case, the free ends of the links C^2 are directly connected by pivots 25 with the end-members of the frame 10 of the rear bed-section. A link 26 connects the rear pivot 25 with a pivot 26^a mounted on a lug 27 carried by the short 80 arm of the rear lever D^2 . In this case, the frame 10 of the rear bed-section moves rearwardly while the structure is being converted from bed-form to sofa-form, during 85 which operation the links C^2 swing rearwardly to a substantially horizontal position. Where the rear bed-section is given a small vertical movement, the forward and rearward shifting of the bed-section is not a serious 90 matter. However, where a more extended 95 lifting movement of the rear bed-section is desired, the use of the slides 11 permits this action to occur without shifting the rear bed-section forwardly or rearwardly to any appreciable extent. In any case, the rear bed-section may be made of greater width where 100 forward and rearward shifting is avoided, as where the slides are employed as connections between the links and the rear bed-section.

Referring again to the construction shown 105 in Figs. 1-13, the conversion from the extended form shown in Fig. 1 to the sofa-form shown in Fig. 2 may be accomplished by removing the cushion C^3 and lifting upwardly and pushing rearwardly on the front bed-section. After the structure has been folded, the cushion may be thrown upon the spring-structure D^3 of the front bed-section which now constitutes the seat of the sofa. The reverse operation will be understood without 115 further description.

As will be understood from Figs. 3 and 110 13, the front bed-section is maintained always in an upright position. That is, it is non-invertible.

The foregoing detailed description has been given for clearness of understanding only, and no unnecessary limitations should be understood therefrom, but the appended claims should be construed as broadly as permissible, in view of the prior art.

What I regard as new, and desire to secure by Letters Patent, is:

1. In a sofa-bed structure, a main frame, a pair of links pivotally carried by each end 130

standard of said main frame, slides mounted on said links, a rear bed-section having a frame mounted on said slides, means for preventing undue shifting of the rear bed-section when it is raised and lowered through the medium of said links, a pair of angular levers independent of said links having short arms pivotally connected with each end standard of the main frame, a front bed-section pivotally connected with the extremities of the long arms of said levers, and link connections between one set of said levers and said first-mentioned links, said levers being adapted to carry the front bed-section bodily in upright position to a position in front of and above the rear bed-section in converting the structure to bed-form and to carry the front bed-section bodily in upright position to a position superposed above the rear bed-section in converting the structure to sofa form.

2. In a sofa-bed structure: a main frame; a pair of parallel links near each end of said frame having pivotal supports on the frame at one horizontal plane; a pair of angular levers at each end of the structure having short arms having pivotal supports on the frame at a higher horizontal plane; a rear bed-section mounted on said links; a non-invertible front bed-section having pivotal connections with the long arms of said levers; and links connecting one pair of said levers with said first-mentioned links whereby the rear bed-section is actuated by swinging the front bed-section.

3. In a soft-bed structure: a main frame provided with end-standards; mounting plates carried by said end-plates; a pair of links pivotally connected with each mounting-plate at a given horizontal plane; slides pivotally connected with said links; a rear bed-section mounted in said slides; a pair of bent levers at each end of the structure having long arms and short arms; pivotal connections between the short arms and said mounting-plates at a plane above the pivotal supports of said links; a non-invertible front bed-section having pivotal connections with the long-arms of said levers; links connecting one set of said levers with said slides; and control-links connected with said mounting-plates and with said rear bed-section.

CHARLES HULTGREN.
